TOWEL CABINET

Application filed March 16, 1925. Serial No. 15,881.

The object of our invention is to provide improved means for limiting the delivery of a towel web to the user, the web being released by the person desiring to use the towel and the feed of the web being automatically checked when a predetermined length has been delivered.

A further object is to provide a simple inexpensive towel feed control which can be easily manipulated and will positively perform its functions under all conditions of use.

Other objects of the invention will appear from the following detailed description.

The invention consists generally in various constructions and combinations all as hereinafter described and particularly pointed out in the claims.

In the accompanying drawings forming part of this specification,

Figure 1 is a vertical sectional view through a towel cabinet with our invention applied thereto;

Figure 2 is a front elevation of the cabinet with a portion of the door broken away showing the position of the rolls therein;

Figure 3 is a sectional view on the line 3-3 of Figure 2;

Figure 4 is a detail sectional view illustrating the action of the feed limiting device during rotation of one of the feed rollers;

Figure 5 is a similar view illustrating how the user may trip the feed limiting device to permit delivery of a length of towel.

In the drawings, 2 represents the side walls of the cabinet, 3 a plate in the bottom thereof and 4 a door through which access may be had to the interior of the cabinet. 5 and 6 represent the towel rolls on which the web of towel is wound and 7 and 8 are the feed rolls having preferably sanded surfaces and adapted to engage the towel rolls to impart a synchronous movement thereto to feed a clean length of towel and wind up a corresponding length of soiled towel. The feed rollers have a driving connection between them as indicated by dotted lines in Figure 1 and the towel rolls are mounted in the cabinet to rest by gravity respectively upon these feed rolls. The clean web of towel

depends through an opening 9 in the bottom of the cabinet and an opening 30 is provided at the rear through which the soiled web is fed upwardly to the soiled towel roll.

It is desirable in a device of this kind to provide means to limit the length of clean towel delivered when a pull is exerted thereon by the user. If this is not done, the user will pull out more clean towel than he needs and there will be a consequent unnecessary waste of the clean towel. To remedy this difficulty in the use of a towel cabinet, we

provide a button or disk 10 fitting within an opening in a plate 11 mounted in the door of the cabinet and in the rear of this button or disk, we provide a plunger 12 slidable in a guide 13 and normally held against inward movement by the tension of a suitable spring

14. We prefer also to provide a recess 15 in the rear of the button 10 and a compression spring 16 interposed between the button and the bottom of the recess to aid in holding the plunger in its forward position and the button flush with the outer face of the door.

The plunger is arranged to move horizontally toward and from the feed roll 7 and said feed roll has a transverse socket 17 formed therein in which a bolt 18 is slidably mounted. The bolt is provided with a wide annular groove 19 to receive a pin 20 mounted in the wall of the socket, said pin allowing said bolt to rotate freely thereon, but contacting with the walls of the groove and limiting the reciprocating movement of the bolt in the socket. The socket preferably has a suitable bushing 21 in which the pin 20 is mounted, said bushing forming a smooth bearing surface for the bolt and allowing it to slide freely in both directions.

In the rotation of the feed roll, the bolt will slide down to the position shown in Figure 4 and thereafter with the rotation of the feed roll the projecting end of the bolt will contact with a stop 22 and thereby the revolution of the feed roll and the towel rolls will be checked. This

checking position of the bolt, as indicated in Figure 5, will be in alignment with the plunger 12 and when the user places a finger on the button 10 and presses in the plunger, the bolt 18 will be pushed in to the position

shown in Figure 5, and thereupon the user grasping the web of clean towel may operate the delivery mechanism to obtain a length of towel sufficient for wiping purposes. The plunger upon being released will return to its normal position and the locking bolt when it assumes the angle shown in Figure 4 will slide down in the socket of the feed roll and be in position to contact with the stop 22 and positively prevent a second revolution of the feed roll until the plunger is again actuated and the bolt released. With this device, therefore, we are able to positively control the feed of the clean towel. The single movement of the plunger will release the locking bolt and it will automatically return to its locking position as the feed roll is revolved, the bolt sliding by gravity in the socket and its end projecting from the roll a sufficient distance to contact with the stop 22 and check a second revolution of the feed roll without any further attention on the part of the user of the cabinet. It will always be necessary for the user to remove the finger from the plunger and allow it to return to its normal position before the bolt can be tripped a second time. It will not, therefore, avail the user anything to keep the finger on the button and hold the plunger at the limit of its inward movement. It must be released and the bolt allowed to become aligned with the plunger before the tripping or releasing operation can be repeated.

We claim as our invention:

33. 1. The combination with a towel cabinet feed roll having a transverse socket therein, and a pin mounted in said socket, of a bolt 40 slideable in said socket and having an annular groove to receive the end of said pin, said bolt having freedom of rotation on said pin but having a limited longitudinal movement, one end of said bolt being projected beyond said feed roll during its rotation, a stop in the path of said projected end and a spring 45 pressed plunger mounted to engage said bolt and move it from a projected to its retracted releasing position.

2. The combination in a towel cabinet, of a roller and a lock therefor, said lock comprising 50 a stop and a freely slideable gravity-actuated bolt associated with, and extending diametrically of said roller, and means under said stop to force the said bolt out of contact with the said stop whereby the roller may be turned, and the bolt dropped by gravity to locking position.

3. A towel cabinet comprising a casing, a feed controlling roller mounted in said casing, the said roller carrying a freely slideable bolt, means for permitting said bolt to be projected outwardly from the surface of said roller, a stop mounted on said casing in the path of said bolt when the latter is in projected position, and a slideable releasing de-

vice mounted on said casing under said stop for releasing said bolt from said stop.

4. A towel cabinet comprising a casing, a feed controlling roller mounted in said casing, a freely slideable bolt carried by said roller, means for permitting said bolt to be projected outwardly from the surface of said roller, a stop mounted on said casing in the path of said bolt when the latter is in projected position and a releasing device mounted under said stop for disengaging said bolt from said stop.

5. In a towel cabinet, the combination of a roller and a locking device therefor, said locking device comprising a stop member and a freely slideable, gravity actuated bolt carried by said roller and extending diametrically thereof, the said stop being so positioned with respect to the path of the projected bolt that when the said bolt contacts with the same the said bolt will be in a substantially horizontal position, and means to retract the said bolt out of contact with the said stop, the substantially horizontal position of the bolt when the roller is in stopped position insuring a retracted condition of the bolt when said bolt retracting means is released.

In witness whereof, we have hereunto set our hands, GEORGE A. STEINER, this 5th day of March 1925, and GEORGE WASILESKI and WILLIAM MURDO, this 9th day of March 1925.

GEORGE ADOLPH STEINER.
GEORGE WASILESKI.

WILLIAM MURDO.
